CLAIM

The ornamental design for a root barrier bracket, as shown and described.

DESCRIPTION

FIG. 1 is a perspective front view of a root barrier bracket, showing my new design;

FIG. 2 is a front side elevational view thereof;

FIG. 3 is a rear side elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is an enlarged view of the bottom portion of FIG. 1.

The ornamental design which is claimed is shown in solid lines in the drawings. FIG. 8 is enlarged in comparison to the other figures to more clearly show detail on the bottom of the figure. The top of FIG. 8 is shown terminating with a symbolic break. The break line is not part of the claimed design, but indicates the continuation of the claimed design shown in the other figures that could not be shown in a single page at the magnification of FIG. 8.
